UNITED STATES PATENT OFFICE.

J. W. SHANKLAND, OF SUMMERFIELD, OHIO.

IMPROVEMENT IN FENCES.

Specification forming part of Letters Patent No. 52,308, dated September 25, 1866.

To all whom it may concern:

Be it known that I, JAMES W. SHANKLAND, of Summerfield, in the county of Noble and State of Ohio, have invented a new and useful Improvement in Fences; and I do hereby declare the following to be a full, clear, and exact description of the nature, construction, and operation of the same, sufficient to enable others skilled in the art to which my invention appertains to make and use the same, reference being had to the accompanying drawing, which forms a part of this specification, and in which the improvement is represented by a perspective view.

The improvement consists in the mode of supporting the lower end of the post; and, secondly, in the mode of securing the post by the side arms and the arms by the keys.

In the drawing, A A are the posts, and B the boards, of a panel of fence. D is a foundation-stone, and E E two iron blocks, which intervene between the lower end of the post and the stone D, to afford ventilation and prevent the gathering of water against the lower surfaces of the post, which would quickly rot it.

To the sides of the post are attached blocks F, and upon these latter rest the arms G G,

which are held by the side blocks, H H, on the keys I, the blocks forming offsets to bind down on the arms. The keys I have caps J to keep dry their upper ends and the junction of the blocks H therewith.

The lower board may be of the same width, and occupy the same vertical position as the blocks F, in which case one of the arms G will rest upon it and assist in maintaining the panel in position.

An end piece, K, completes the finish of this portion, and assists in binding the portions together. L is the cap on the post.

Having thus described my invention, what I claim therein as new, and desire to secure by Letters Patent, is—

1. The arrangement of the post A, iron blocks E E, and foundation-stone D, as described.

2. The mode of securing the arms and post in position by the combination of blocks H, the keys I, arms G, and the blocks F on the post A, substantially as described and represented.

J. W. SHANKLAND.
